APPARATUS FOR SPREADING SURFACING MATERIALS

Carl Gunnar Lindgren, Ljungby, Sweden, assignor to Vibro-Plus Corporation, Woodside, N. Y., a corporation of Delaware

Application February 20, 1952, Serial No. 272,648

3 Claims. (Cl. 94—46)

The present invention relates to apparatus for spreading surfacing materials and, more particularly, to apparatus for spreading concrete in road construction.

Surfacing materials are often spread laboriously by hand, such as where a concrete carrying truck is backed up over the general area to be surfaced, and the concrete is permitted to pour through a short chute which is swung here and there over a limited region. The resulting piles are spread manually, the truck is driven forward a few feet, and the process is repeated.

Concrete spreaders employing movable hoppers have been used to some extent but these spreaders suffer from the disadvantage that the hoppers must be filled from appreciably above the ground level in order that there may be sufficient static pressure to produce satisfactory spreading of the concrete as the hopper is moved. Some intermediate conveyor must be utilized to fill the hopper of the concrete spreader or the concrete carrying truck must be driven onto a platform above the surrounding ground level to gain the necessary height above the area to be surfaced. Both these expedients are troublesome and expensive and have severally limited the utility of concrete spreading hoppers.

It is a primary object of the invention to provide an arrangement associated with a surfacing material spreading hopper to simplify the filling of the same.

According to one aspect of the invention, this object is attained by rendering the hopper of a surfacing materials spreader tilttable from an upright, emptying position to an inclined, filling position. This permits surfacing materials to be conveniently discharged into the hopper in a heap lying on a substantially horizontal side. The hopper may then be returned to its upright position, whereupon the contents flow out of a discharge opening under the action of adequate static pressure.

In order that the invention may be more clearly understood, it will now be described with reference to the accompanying drawings, wherein:

Fig. 1 is a plan view of apparatus employing a tilttable hopper for spreading surfacing materials.

Fig. 2 is a side elevation view of the apparatus shown in Fig. 1, and

Fig. 3 is an elevation view of the apparatus showing the hopper in filling position.

Referring now to the drawings, a surfacing materials spreading apparatus is shown comprising a generally rectangular carriage 11 formed with parallel side members 12 and 13 which are connected near a material-receiving end 14 by transverse beams 15 and 16 and near the opposite end 17 by a transverse beam 18. The carriage 11 is supported by pairs of wheels 19, 21 and 22, 23 for movement along tracks 24 and 25 respectively, lying perpendicularly to the side members 12 and 13 and defining the side boundaries of an area 26 to be covered by surfacing material 27.

The carriage 11 supports a hopper 28 which has vertical sides 29 and 31 parallel to and between the side members 12 and 13 of the carriage and sloping sides 32

2

and 33 which converge downwardly to form a discharge opening 34. The hopper 28 is supported by pairs of wheels 35, 36 and 37, 38 in a normally upright emptying position with the discharge opening 34 slightly above the level of the tracks 24 and 25. The wheels 35, 36 and 37, 38 roll on inner and outer guideways 39 and 41, respectively, carried by the side members 12 and 13 and permit movement of the hopper 28 towards and away from the ends of the carriage 11, that is, at a right angle to the direction of movement of the carriage 11 along the tracks 24 and 25.

The guideways 39 and 41 are parallel in the vertical plane until near the material-receiving end 14 of the carriage 11 where they diverge, the inner guideways 39 sloping downwardly and the outer guideways 41 curving upwardly. The guideways 39 end at a point close to the ground for the purpose of bringing front wheels 35 and 36 of the hopper 28 as near ground level as possible. The hopper 28, upon being propelled towards the material-receiving end 14 of the carriage 11, is progressively tilted by the action of the guideways 39 and 41 about a horizontal axis parallel to the end 14 and perpendicular to its own direction of movement until it assumes a sloping filling position, as shown in Fig. 3. In the filling position the side 32 of the hopper 28 is substantially horizontal, only slightly above the level of the area 26 to be covered, and off to one side of such area. Accordingly, the hopper 28 can be filled by merely tipping from a truck standing on the ground level. The side 32 of the hopper 28 is preferably longer than the opposite side 33 in order to accommodate concrete or other surfacing material in a pile and to permit a truck to be driven, if desired, into the load-receiving opening of the hopper. When the hopper 28 is again rolled over the area 26, it resumes its upright emptying position and the surfacing material 27 pours from the discharge opening 34 as it progresses across the width of the area 26.

Movement may be imparted to the hopper 28 by a motor 42 which operates through a gear box 43 having a clutch and reversing control lever 44. The gear box 43 is coupled by means of sprockets 45 and 46 and connecting chain 47 to a shaft 48 on which is keyed a driving sprocket 49. An endless chain 51 is stretched between the sprocket 49 and an idler sprocket 52 mounted at the other end of the carriage 11. A link 53 having one end pivotally connected to a point on the chain 51 and the other end pivotally connected to the side 29 of the hopper 28 completes the drive mechanism. It is to be understood that a second chain and link may be employed on the opposite side 31 of the hopper 28 in order to provide a balanced propulsive force.

When electric power is available the wheels 37, 38 may be driven directly by a motor and the endless chain 51 and the link 53 dispensed with. With this arrangement the wheels 37, 38 would be provided with teeth and the outer guideways 41 formed as a rack.

In order that the weight of the hopper 28 in its filling position does not place an uneven load on the wheels 35, 36 and 37, 38, a load-relieving girder 554 may be placed under the horizontal side 32 of the hopper 28 or shock absorbers may be permanently attached to the side 32.

Rough leveling is provided by a leveling board 55, which is fastened in an adjustable vertical position to the side 32 of the hopper 28.

The wheels 19, 21 and 22, 23 supporting the carriage 11 are illustrated as having flanges in order that they may be guided by the tracks 24 and 25, respectively. It may, of course, in some cases be preferable to provide rubber-tired wheels where the carriage 11 is intended to roll on the ground. The tracks 24 and 25, however, are

convenient since they provide reference edges for the final leveling and surface finishing operations. The wheels 19, 21 and 22, 23 are mounted on axles having appreciable length in order that the spacing between the wheels 19, 21 and the wheels 22, 23 may be altered to accommodate different track widths.

It is to be understood that if the ground conditions are of such nature that a truck cannot be driven to the hopper without a special ramp or when material spreading takes place above the normal ground level, the necessary scaffolding does not detract from the advantages of the present invention. In order to avoid the manual shifting of planking in the former case each time the spreader is moved, the hopper may, of course, be fitted with a suitable extension which will serve as a ramp for the truck.

I claim:

1. Apparatus for spreading surface materials comprising a carriage movable along an area to be surfaced, guideway means on said carriage including at least two pairs of substantially horizontal guideways extending across said carriage, the respective pairs being laterally spaced apart to define an open space therebetween and the respective guideways of each pair being laterally offset, an open-ended hopper having one side formed longer than its opposite side, said hopper including at least two pairs of wheel means engaging the respective guideways and carrying the hopper in an upright emptying position on said carriage for spreading material across the area through said open space, respective pairs of said wheel means being spaced apart in the direction of movement of the hopper across the carriage, means for tilting the hopper to an inclined filling position at one side of the carriage to dispose said longer side horizontally for loading said surface materials, said tilting means including a downwardly inclined section for one guideway of each pair of guideways engaged by the pair of said wheel means nearest said one filling side of the carriage, said tilting means also including an upwardly inclined section for the other guideway of each pair of

guideways engaged by the other pair of wheel means, the downward and upward inclination of said sections commencing at points spaced apart in the direction of movement of the hopper across the carriage, the downwardly inclined sections being nearer to said one filling side of the carriage than said upwardly inclined sections, chain means movable in a substantially horizontal direction between the extremities of movement of the hopper on the carriage, link means pivotally connected to the hopper in the vicinity of its upper end and fastened to the chain means, and means for driving the chain means in either direction to pull the hopper to and fro on the carriage in its upright emptying position and to pull the hopper along said inclined sections for tilting it to and righting it from the inclined filling position.

2. Apparatus as defined in claim 1 wherein means are provided to engage the lowest side of the hopper when it is in its inclined filling position to relieve the load on the wheel means.

3. Apparatus as defined in claim 1 wherein a leveling member is attached to the hopper adjacent the discharge opening on the side of the hopper nearest the filling side of the carriage for roughly leveling the discharge material.
